UNITED STATES PATENT OFFICE.

HERBERT IVERSEN, OF CHICAGO, ILLINOIS.

SEPARABLE BUTTON.

1,328,432.

Specification of Letters Patent. Patented Jan. 20, 1920.

Application filed August 22, 1918. Serial No. 250,919.

To all whom it may concern:

Be it known that I, HERBERT IVERSEN, a subject of Christian X, King of Denmark, residing at Chicago, in the county of Cook 5 and State of Illinois, have invented certain new and useful Improvements in Separable Buttons, of which the following is a specification.

My invention relates to a separable button 10 having a head secured to neck and base members equipped with a pin arranged to be passed through an interposed fabric and detachably engage a locking disk upon the opposite side of the fabric. The object of 15 my invention is to provide a secure and desirable fastening means for a button of this class, whereby the button may be quickly and easily applied, and as readily removed if desired, without injuring the 20 cloth, thus enabling the position of the button to be changed to suit the wearer of any garment to which it may be applied, or removed while the garment is being laundered, or to permit the button to be applied 25 to another garment. With the foregoing and incidental objects and advantages in view I have invented the separable button herein-after described in detail, the essential elements of my invention being more particu- 30 larly pointed out in the appended claims.

In the drawings Figure 1 is a perspective of my novel separable button applied to a piece of cloth; Fig. 2 is a central vertical section of the same; Fig. 3 is a top plan view 35 of the locking disk which forms one member of my device; Fig. 4 is a bottom view of the same; Fig. 5 is a top view of a locking disk having a modified form of locking slot and a pin adapted to coöperate therewith; and 40 Fig. 6 is a diametrical section, partly in perspective, showing a modified form of my invention.

The same reference characters designate 45 the same parts in all the figures of the drawing.

Referring more particularly to Figs. 1 and 2 of the drawing, the upper or outer member A of my separable button comprises a head portion 1 which constitutes the button 50 proper, a neck or shank 2 and a foot plate or base plate 3, all of which parts may in many cases be conveniently formed integrally, although if desired they may be formed separately and secured together in 55 any convenient manner. Secured to the member A and projecting from the plate 3

axially of the neck 2 is an L-shaped pointed locking pin 4 which preferably is formed of metal of maximum strength and stiffness. The shaft of the pin in the present 60 instance, and preferably, extends through the base plate 3 into the neck 2 of the button. If desired the pin may be thickened adjacent its bend to strengthen it at that point.

The locking disk B which constitutes the lower or inner member of my device and is preferably of the same diameter as the foot plate 3 of the member A is formed with a radial slot 5 to permit insertion there- 70 through of the locking pin 4, the central portion of the lower face of the disk being cut away to form a spiral cam 6 which rises gradually from its lowest point on one side of the slot to its highest point on the opposite side. This cam is arranged to co- 75 operate with the end portion of the locking pin, and the circular peripheral wall or rim 6^a serves to protect the pin point and prevent its accidental dislodgment after the 80 button is applied to a garment.

The locking disk is preferably made as thin as possible in order that the cam may have a relatively slight pitch, with consequent strong wedging action, and to avoid 85 an undesirable inward protuberance. If desired, the lower face of the disk may be covered or faced to conceal the cam surface and the end of the locking pin, and the disk may be formed with engaging faces adapted 90 to coöperate with a wrench to facilitate fastening the members together.

It will be understood from the foregoing description that the button may readily be applied to a garment by passing the locking 95 pin 4 of the member A through the fabric and engaging the member B therewith by passing the pin through its slot 5, and giving one of the members a rotary movement 100 to clamp them together on the interposed fabric. When the button is removed by a reverse operation, the fabric will be but slightly, if at all marred, owing to the fact that it was penetrated only by a pointed, slender, needle-like member. The fastening 105 is nevertheless secure, since the tensile strength of the pin is sufficient to clamp the base plate 3 of the member A and the locking disk B (both of which have extended engaging faces) tightly together. These 110 two coöoperating faces may be plain, as shown in Fig. 2, or one or both may be

more or less cupped, as in the modified form of my invention hereinafter described, and illustrated in Fig. 6.

- The length of the shaft of the locking pin 5 is of course such that when applied to the fabric for which it is designed the end portion of the pin will coöperate with the cam surface 6 of the locking disk to clamp the members firmly against the fabric, and 10 preferably the shaft should be slightly less in length than the thickness of the cam at its highest point, in order that the parts may be locked together without the interposition of a fabric.
- 15 In Fig. 5 I have illustrated a modified form of locking slot in the locking disk, and a locking pin adapted to coöperate therewith in which the shaft of the pin, marked 7, has a diameter greater than the width of 20 the end portion 8 of the pin, the inner end 9 of the slot being enlarged to receive the pin shaft 7, a construction which prevents the pin from slipping away from its central position in the locking disk.
- 25 As shown in Fig. 6, the button head, marked 10, may be flexibly connected to the looped end of the pin 11 by means of a ring fastened to it, or otherwise flexibly connected, instead of being connected rigidly 30 to the neck portion of the button member, as in the form of my invention first above described.

From the description of my invention above given it will be obvious that my novel 35 separable buttons may be very quickly applied, and that they are therefore well adapted for use in the manufacture of clothing in large quantities, particularly such as is made of rather thick material, as for instance, 40 coats, trousers, and men's garments generally, and that in the manufacture of uniforms and other varieties of clothing which it is important to supply quickly much time and labor can be saved. It is further ob- 45 vious that my invention may be applied to other articles than clothing, and that it may be used to fasten together layers or plies of any sort of material as paper or leather and may be used for attaching such articles 50 as rings, buckles, or the like to curtains of

tents or other articles made of textile fabrics, or to thin material of any sort.

I claim:

1. A separable button comprising a button head and a base plate to which said button head is secured, an L-shaped metal pin being secured to said base plate, and a locking disk coöperating with said pin and arranged to clamp an interposed fabric against said base plate. 60

2. A separable button comprising a button head and a base plate to which said button head is secured, an L-shaped metal pin being secured to said base plate, and a locking disk formed with a spiral cam coöperating with said pin and arranged to clamp an interposed fabric against said base plate. 65

3. A separable button comprising a button head and neck and base plate members rigidly secured thereto, said base plate being equipped with an L-shaped metal pin secured axially of the neck member, and a locking disk coöperating with said pin and arranged to clamp an interposed fabric against said base plate. 70

4. A separable button comprising a button head and integral neck and base plate members to which said button head is secured, said neck and base plate members being equipped with an L-shaped metal pin 75 extending through the base and into the neck, and a locking disk coöperating with said pin and arranged to clamp an interposed fabric against said base plate.

5. In a separable button or the like, fas- 80 tening means comprising a base plate secured to the button and an L-shaped pointed pin having its shaft secured to said plate, and a locking disk having on its outer face a spiral cam coöperating with the end por- 85 tion of said pin. 90

6. In a separable button or the like, fas- 95 tening means comprising a base plate secured to the button and an L-shaped pointed pin having its shaft secured to said plate, and a locking disk formed with a radial slot for the insertion of the pin and having on its outer face a spiral cam coöperating with the end portion of said pin. 95

HERBERT IVERSEN.
